UNITED STATES PATENT OFFICE.

COMMODORE R. MILLER, OF WOODLAWN BOROUGH, PENNSYLVANIA, ASSIGNOR,
BY MESNE ASSIGNMENTS, TO SUPERIOR GAS IMPROVEMENT COMPANY, OF
PITTSBURGH, PENNSYLVANIA, A CORPORATION OF ARIZONA.

PROCESS OF MANUFACTURING GAS.

1,061,861.

Specification of Letters Patent. Patented May 13, 1913.

Application filed September 7, 1912. Serial No. 719,049.

To all whom it may concern:

Be it known that I, COMMODORE R. MILLER, a citizen of the United States, and residing in the borough of Woodlawn, in the 5 county of Beaver and State of Pennsylvania, have invented or discovered new and useful Improvements in Processes of Manufacturing Gas, of which the following is a specification.

10 My invention consists in a new and improved process of producing gas for illuminating and other purposes.

My object is to produce gas from coal and similar material, and by means of my 15 new process I greatly increase the percentage of value extracted from the raw material, expedite and cheapen the operation, and obtain a combined water and coal gas of the highest efficiency with no resulting 20 residue or by-products.

Generally speaking, my process is as follows: In a plurality of adjacent generating chambers contained in a common furnace I bring beds of suitable fuel, such as coke, to 25 a state of high combustion. When said fuel beds have become incandescent, I spread upon the top of each of the same a thin bed or layer of fine or nut coal. The drafts or air-blasts used to incite combustion of the 30 coke are now cut off and all egress to atmosphere closed. I now force dry steam up through the coke and coal beds in one of said generating chambers, decomposing the steam and forming uncarbureted water gas 35 intermingled with the lighter hydro-carbons of the coal released by the coking process. The coking process going on in the remaining generating chambers releases the lighter hydro-carbons which 40 rise and mingle with the products of combustion from the first mentioned generating chamber. To prevent packing and expedite coking, I agitate the coal beds in all of the generating chambers during 45 the coking process, by means of pokers, or other suitable devices. The products from the generating chambers meet and intermingle in the top of the furnace and are then led through a highly heated retort 50 which is located above the generating chambers, passing thence to a wash-box. The passage of the products through the retort is retarded by means of baffles and said retort is preferably of substantially U-shape

to give additional length of passage within 55 the limited area of the furnace. The effect of passing the products of generation through the highly heated retort is to change the vapor-gases into a fixed gas, the particles being broken up and mingled in a 60 permanently gaseous state by prolonged contact with the highly heated walls and baffles of the retort. As the operation proceeds the heavier hydro-carbons of the coal beds are released, gasified and fixed in the 65 same manner. When the temperature in the generating chamber first referred to falls below the degree required to decompose the steam, the steam is cut off from said generating chamber and introduced into another 70 of the generating chambers and the operation repeated as above described. When the temperature of the second generating chamber falls below that required to decompose steam, the steam is cut off therefrom and 75 introduced into a third generating chamber, until all the generating chambers have been so treated in turn. I am thus enabled to greatly prolong the gas-production from a given amount of coal over and above the 80 period of production where steam is introduced into all of the generating chambers simultaneously and am also enabled to gasify and fix all the volatile elements of the coal. After all the coal beds have been 85 thoroughly coked and their gaseous value realized, I reopen the furnace stack and admit forced draft to restore the coke beds to incandescence whereupon I recharge with coal and repeat the operation above described. 90

In the case of small plants, I may use but one generating chamber using the U-shaped and baffled retort to fix the volatile products of the coal.

In the accompanying drawings, Figure 1 95 is a longitudinal, vertical section of my apparatus taken along the line I—I in Fig. 3; Fig. 2 is a front elevation of the same; Fig. 3 is a section of the same along the line III—III in Fig. 1; Fig. 4 is a horizontal 100 section of the same along the line IV—IV in Fig. 1; Fig. 5 is an enlarged detail of the method of mounting the poker shown in Fig. 3; Fig. 6 is an enlarged detail illustrating the method of introducing the steam into 105 the combustion chamber and separating the water therefrom, and Fig. 7 is a vertical section along the line VII—VII in Fig. 2.

The following is a detailed description of the drawings: The apparatus is in the form of an inclosed furnace A containing a plurality of generating chambers, such as 1, 1^a, 1^b, separated by vertical partitions 2, 2^a, which extend up into the upper portion of the furnace and from front to rear wall thereof, a large chamber B occupying the top of the furnace. The tops of the partitions are connected together and to the end walls of the furnace by pairs of flat-topped arches 3-3, spaced apart to form central flues 4-4 and spaced from the front and rear walls of the furnace to form side flues 5-5. I thus have two rows of arches in alignment adjacent respectively to the front and rear walls of the furnace, forming a table upon which rests a retort C, preferably made of fire-clay, and of substantially a U-shape. Said retort is preferably of semi-circular cross-section and formed in two parts or legs 6 and 6^a, removably connected together, as at 7. The free end of leg 6 is open and located above the first generating chamber 1 while the free end of leg 6^a connects with a chamber 8 from which rises a stack 9 provided with a closing valve 9^a. The outer end of chamber 8 communicates with a drum 10 from which a pipe 11 leads to the wash-box 12 from which the pipe 13, in turn, connects with a condenser, not shown.

14-14 represent doors in the end wall of the furnace A leading into chamber B and through which the legs 6 and 6^a of the retort B may be introduced or withdrawn, as required.

The retort C is provided with internal baffles 15-15 which retard the passage of the volatile elements through said retort thus holding them in the zone of extreme heat until thoroughly gasified.

A second stack 16 leads upward from the chamber B adjacent to the open end of leg 6 of retort C, said stack being provided with a valve 16^a to close the same tightly when desired.

17-17 represent ash-doors in the front wall of the furnace below the level of the grate-bars 18-18 of the generating chambers.

19-19 represent clinker doors in the front and rear walls of the furnace above the level of said grate-bars, and 20-20 represent charging doors at a higher level, while 21-21 represent charging platforms.

D is an air-blast main extending along the front of furnace A and connected with the ash-pits of the various generating chambers by means of branch-pipes 22-22 controlled by gates or valves 23-23.

E is a steam line extending along the front of the furnace A and connected by branch-pipes 24-24 with the ash-pit of each of the generating chambers. Said branch-

steam-pipes discharge at the center of said ash-pits through upturned reduced nozzles 25 which discharge against an inverted cone shaped spreader 26 suspended from the center grate-bar 18, thus spreading the escaping steam and precipitating the water carried thereby. Each pipe 24 is provided with a valve 27 so that the steam may be admitted to or cut off from the individual generating chamber, as required.

Piercing the rear wall of each of the generating chambers below the charging doors 20-20 is an inwardly expanding orifice 28 in the throat of which is secured a ball-socket 29 in which is mounted the ball 30 provided with a diametrical bore in 80 which is inserted the packing-gland 31. A poker or agitating tool 32 is slidingly mounted in said gland 31. It is evident that the tool is thus given an extended zone of action whereby every portion of the coal beds may be conveniently reached and agitated during the coking operation.

The operation of my apparatus in performing my process is as follows: The valve 9^a in stack 9 is opened and valve 16^a in stack 9^a is closed, so that the products of combustion must pass about and through the retort C in escaping to atmosphere. Coke is charged in each of the generating chambers 1, 1^a and 1^b to a little below the level of 95 charging doors 20-20 and ignited. The valves 23-23 of air-blast pipes 22-22 are now opened and the coke beds brought to an incandescent state. The interior of the furnace, the walls of chamber B and the walls 100 and baffles of retort C are thus brought to a high heat. The valve 9^a is now closed cutting off egress to atmosphere and the valves 23-23 are closed cutting off the entrance of air. Fine or nut coal is now 105 charged through doors 20-20 forming an evenly distributed bed over the surface of the coke beds to a thickness of about two inches. The charging doors are now tightly closed. The lighter hydro-carbons now begin to rise as coal-gas from the coal beds which are agitated with the pokers 32-32 to expedite and assist the coking operation, said gases rising through flues 4-4 and 5-5 into the chamber B and entering 115 and working their way through the retort C into the chamber 8 and thence through drum 10 into the wash-box 12. Steam is admitted into the coke bed of generating chamber 1, passing up through the coke bed and 120 decomposing to form water gas which rises and mingles with the coal gas in its passage through the chamber B and retort C. As the operation proceeds the heavier hydro-carbons rise from the coal beds and pass 125 in the manner above described to the wash-box. When the temperature of the coke-bed in generating chamber 1 falls below that

required to decompose the steam, the steam is cut off from said chamber and introduced in like manner into chamber 1^a, whence it is cut off when the coke bed in chamber 1^a becomes chilled below the point of the decomposition of steam, whereupon the steam is cut off of said chamber and introduced into chamber 1^b. This operation is continued until all the generating chambers have been thus treated. The volatile elements arising from the coal beds are superheated in chamber B and in their passage through the retort C are heated and broken up by their contact with the walls and baffles of the retort, so as to become thoroughly gasified and fixed. When the coal beds have become thoroughly coked, I reopen the valve 9^a of stack 9 and turn on the air-blast to bring the coke beds back to incandescence. Where there is danger of overheating the retort C and causing it to burn the gases, as indicated by the formation of lamp-black, I do not open the valve 9^a of stack 9 but open the valve 16^a of stack 16 permitting the heat to escape during the firing-up without passing through the retort C.

By the introduction of steam successively into the various generating chambers, I am enabled to prolong the gas making operation until the entire gaseous value of the raw material is realized insomuch as only a fraction of the incandescent coke is chilled at a time, and the interior of the furnace and the retort are maintained at the high temperature necessary to release the volatile elements of the raw material and gasify and fix the same. Were the steam admitted simultaneously to all the generating chambers, the coke beds would become chilled before the complete gasification and fixing of the volatile elements, resulting in quantities of

residue and by-products, such as tar, all of which are gasified by my improved process.

The agitation of the coal during the coking process expedites and renders the same more complete.

The form and character of retort used by me is important. By forming the same in the contour shown and providing the internal baffles, I prolong and intensify the treatment of the gases and thoroughly break up and fix the volatile elements of the raw material. In the case of a small plant, I may provide the furnace with but a single generating chamber to be used in connection with my retort.

What I desire to claim is:—

1. The process of manufacturing gas, which consists in blasting a bed of coke to incandescence; then cutting off the blast; then charging a layer of coal upon the coke-bed; then turning on steam to make water-gas and simultaneously distilling the coal-bed by passing the steam upward therethrough; and simultaneously agitating the bed of coal during the run.

2. The process of manufacturing gas, which consists in blasting to incandescence a plurality of adjacent, spaced coke-beds; then cutting off the blast; then charging a layer of coal upon each coke-bed; then turning on steam to make water-gas and distilling the coal-beds successively by passing the steam upward through said coal-beds successively; and simultaneously agitating the beds of coal during the run.

Signed at Pittsburgh, Penna., this 10th day of June, 1912.

COMMODORE R. MILLER.
